UNITED STATES PATENT OFFICE.

GUSTAV STICKLEY, OF NEW YORK, N. Y.

OPEN FIREPLACE.

1,068,545.

Specification of Letters Patent.

Patented July 29, 1913.

Application filed March 15, 1912. Serial No. 684,039.

To all whom it may concern:

Be it known that I, GUSTAV STICKLEY, of New York city, in the county of New York, in the State of New York, have invented 5 new and useful Improvements in Open Fireplaces, of which the following, taken in connection with the accompanying drawings, is a full, clear, and exact description.

This invention relates to certain improvements in open fire places for dwellings and other buildings and refers more particularly to means for heating and circulating currents of air and distributing the heated air to one or more local or remote parts of the 15 building in which the fire place is located.

The main object is to cause the heated products of combustion and air to travel across relative large areas of comparatively thin radiating surfaces within a hollow wall 20 so as to form a receiving chamber from which the heated air may be distributed to any part or parts of the building.

Another object is to conceal the entire radiating medium within the hollow wall 25 or chimney in which the fire place is built, thereby permitting such fire place to be constructed and operated in the usual manner without reducing its efficiency in heating the room in which it is located or exposing any 30 part of the radiator.

In other words I have sought to produce a radiator of the class described which may be easily and quickly incorporated in any style of fire place without detracting from 35 the general characteristics of such fire places.

Other objects and uses relating to specific parts of the fire place will be brought out in the following description: In the drawings Figure 1 is a perspective view of a fire place 40 embodying the various features of my invention, a portion thereof being broken away to show the concealed parts of the apparatus. Fig. 2 is a perspective view of the detached sheet metal radiator box forming a concealed part of the fire place. Fig. 45 3 is a perspective view of a portion of the fire place seen in Fig. 1 showing the same in transverse vertical section. Fig. 4 is a horizontal sectional view through the 50 low supporting wall for the fire place showing particularly the ash pit and cold air flue therein. Figs. 5 and 6 are similar horizontal sectional views through the fire place taken respectively on lines 5-5 and 6-6, Fig. 1 55 showing particularly in Fig. 5 the relation of the radiator to the air chambers at the sides,

while Fig. 6 shows more particularly the position of the smoke flue in relation to the radiator box.

This fire place comprises a hollow upright 60 wall —1— which is supported upon a suitable foundation —2— within the room of a building between a floor as —a— and ceiling —b— of a superposed floor —a'— and may be constructed of brick, tile or other 65 heat resisting material in any desired design, the central front portion of the hollow wall —1— being provided with a suitable fuel opening —3— extending upwardly from the plane of the floor —a— and also ex- 70 tends rearwardly some distance beyond the front wall for allowing the fuel to be placed back of the front face of the fire place and establishing direct communication with a superposed fire or draft passage 75 presently described.

The hollow wall —1— forming the fire place, and its supporting wall or foundation —2— are preferably the same width somewhat greater than the width of the fuel 80 opening —3— so as to extend equi-distant to opposite sides thereof, the foundation —2— being also hollow to form an ash pit —4— while the sides of the hollow wall or fire place —1— are also hollow forming air 85 chambers —5— communicating with the interior or main chamber —6—.

The chambers —5— and —6— preferably extend from floor to floor and constitute what may be termed air receiving and distributing chambers. That is, the cold air 90 may be taken from the outside atmosphere through an inlet —7— into the base of the air chamber —6— or may be taken from the room near the lower floor line through 95 grilled openings —8— in the side chambers —5— as shown more clearly in Figs. 1, 2 and 5, while the heated air in the upper part of the chamber —6— may be delivered 100 into the adjacent room through a grilled opening —9— in the rear side of the wall —1— or other suitable conduits —10— in the superposed floor —8— through which the heated air may be conveyed to the next superposed room or to other portions of the 105 buildings as may be desired.

When wood fuel is used, the upper end of the ash pit —4— may be closed by a suitable plate —11— adapted to be supported in any desired manner hereinafter 110 described for receiving and supporting suitable andirons (not shown) but when coal

fuel is employed, I preferably provide a grate —12— which is supported upon a frame work presently described, such frame work being also adapted to support a grill front —13—.

The grate —12— is supported within and upon a rectangular frame —14— which in turn is supported at its ends in a horizontal position upon ledges —15— on the side walls 10 of the fuel opening —3— some distance above the plane of the floor —a—, thereby leaving an intervening draft passage between the front side of the frame and floor, said passage being closed by a removable 15 shield or plate —16— to prevent the exit of dust into the room and also to cover the ends of the grate bars.

The grate preferably comprises a series of 20 rotary grate bars journaled in suitable bearings in the front and rear sides of the frame —14—, it being understood that the front ends of the grate bars extend forwardly slightly beyond the front side of the frame —14— for the reception of a suitable shaker 25 when the shield plate —16— is removed from its operative position.

The grilled front —13— of the fire box is 30 removably supported in the front side of the frame —14—, in an upright position thus permitting it to be removed by simply lifting it upwardly from said frame. In like manner the entire frame —14— may be 35 easily removed by simply lifting it from its supporting ledges —15— thereby permitting the fire place to be easily and quickly changed for burning wood or coal fuel.

Air heating device.—I have now described 40 the general construction of the fire place exclusive of the air heating device or radiator which is preferably incorporated in the hollow wall during progressive building and 45 consists of an upright sheet metal box or casing —17— supported centrally within the air chamber —6— with the major portion thereof spaced apart from the front, rear and side walls of the hollow wall —1— so as to leave a clear open space around 50 practically the entire surface area of the box and extending from the base of the fuel opening —3— to a plane some distance above the upper side of said opening and from side to side thereof for the purpose of affording a relatively large heating and radiating area. As shown in the drawings this 55 box is preferably made of sheet metal and comprises upright front and rear walls —18— and —19—, intermediate upright partitions —20— and —21—, opposite end walls —22— and —22'— and top walls —23— and —23'— all of which parts are 60 united to form a unitary structure with air and gas tight joints. The lower edge of the front wall —18— terminates a distance above the bottom of the box corresponding 65 to the height of the fuel opening —3— to

form a corresponding fuel opening in the front of the box and is preferably deflected forwardly against the inner face of the front side of the hollow wall —1— just above the fuel opening —3— so as to form an air and gas tight joint therewith, the remaining portions of the box front —18— being substantially flat and spaced apart from the inner face of the front side of the wall —1— so as to form additional air space communicating with the air chamber —6—.

The lower edge of the rear side —19— of the radiator box is provided with a lateral offset 39 resting upon the upper edge of the foundation wall —2— at the rear of the ash pit —4— and serves to support practically the entire weight of said radiator box, the connection between the front wall of said box and adjacent side of the hollow wall —1— serving to additionally support the 85 box in its operative position. The lower portions of the sides —22— and —22'— extend forwardly some distance beyond the upper portions above the ledge as —18'— and are closely fitted against the side walls 90 of the fuel opening —3— to form air and gas tight joints therewith and to additionally support the radiator box against lateral movement. The upright partition —20— consists of a flat sheet metal plate rigidly 95 secured at its ends to the corresponding ends of the box between the front and rear sides —18— and —19— and apart therefrom, said partition extending from the plane of the base of the fuel opening —3— to a plane 100 some distance above the upper side thereof and in proximity to but spaced apart from the top wall —23—, thereby dividing the interior of the box into front and rear combustion chambers or fire passages —24— 105 and —25— communicating with each other above the upper edge of the partition —20—, the front chamber being in direct communication with the fuel opening —3— while the rear chamber —25— extends downwardly 110 from the upper edge of the partition —20— to the bottom of the box and therefore across the entire area and at the back of the fuel opening. It will also be seen that the cold air which enters the chamber —6— through 115 either of the inlet openings —7— or —8— also comes in contact with all portions of the front, back top and ends of the radiator box and also with all portions of the partition plates —26— and —26'—, thereby absorbing the heat radiated by said box and 120 delivering it into the chamber —6— from which it may be distributed to adjacent rooms or other parts of the building in the manner previously described.

In order that the heat radiated by the sides of the hollow partition —21— may be most efficient in heating the air in contact therewith, the upper side of the space between the partition plates —26— and 130

—26— is left open while the greater portions of the ends of such space are closed by the end walls —22— and —22'—, leaving relatively small air inlet openings —32— in said ends communicating with the lower portion of the chamber —27— in the hollow partition —21— so as to cause the cold air to travel as nearly as possible across the entire areas of said plates. It will also be observed that the air which may enter the space between the front —18— of the box and adjacent side of the hollow wall —1— will also be heated and delivered into the distributing chamber —6—.

15 The smoke flue or chimney —30— may be located in any convenient position but is preferably incorporated in one corner of the hollow wall —1— and rests upon suitable girders —33— and —34—, the girders —33— being supported in the front and rear sides of one end of the hollow wall —1— just above the plane of the upper side of the fuel opening —3— or rather below the plane of the smoke outlet —29— in the radiator box —17— so that when the smoke flue —30— is built up from the girders —33—, a suitable opening is left therein for registration with the smoke outlet —29—. The girder —34— is also supported in the front and rear sides of the adjacent end of the hollow wall —1— just over the corresponding end of the radiator box, thus affording additional support for the chimney which may be extended to any height 35 through the roof of the building or may be connected to any other smoke flue if desired.

40 The front face of the partition —20— immediately back of the fuel opening —3— is covered with a facing —40— of brick, tile or other heat resisting material extending from the base some distance above the upper side of said fuel opening to not only conceal this portion of the radiator box from view but also to protect the partition 45 against burning out at its junction with the fire box or grate, said facing being supported upon a forwardly projecting ledge —39— on the lower edge of the partition and extends from side to side of the fuel opening so as to form air and gas tight joints therewith.

What I claim is:

1. A fire place comprising an upright hollow wall having a fuel opening in one side, a sheet metal casing within the hollow wall having front and rear fire chambers, and an intermediate air chamber, the latter communicating with the interior of the hollow wall, said fire chambers communicating with each other below the lower side of the air chamber, the lower edge of the front side of the casing terminating against the upper side of the fuel opening of the wall to form a gas tight joint therewith, and a partition within the front fire chamber rising

from the base above the upper side of the fuel opening and terminating below the upper side of the fire chamber.

2. In an open fire place, an upright hollow wall having a fuel opening and a smoke outlet, a smoke flue communicating with the outlet, the interior of said wall having a cold air inlet and a hot air exit, a hollow upright metal casing supported within the hollow wall and extending from the plane of the base some distance above the upper side of the fuel opening, the front side of the casing having a fuel opening communicating with the fuel opening in the wall and having the lower edge of its front wall fitting against the upper side of the fuel opening in the wall to form a gas tight joint therewith, the remaining portions of said casing exclusive of its rear side being spaced apart from the inner sides of the hollow wall, said casing having front and rear fire chambers and an intervening air chamber, the latter communicating with the interior of the hollow wall, said rear fire chamber having a smoke outlet connected to the smoke outlet in the hollow wall, and a partition projecting upwardly from the plane of the base of the fuel opening within the front fire chamber and spaced apart from the front and rear sides thereof, said partition terminating some distance below the upper side of said front fire chamber to allow the passage of the products of combustion over the upper edge thereof.

3. An open fire place comprising a hollow wall having a fuel opening and a hollow sheet metal box within the hollow wall at the back of the opening and also provided with a fuel opening in its front side registering with the fuel opening in the hollow wall, said box having a fire passage provided with a smoke outlet but otherwise cut off from communication with the interior of the hollow wall.

4. An open fire place comprising a hollow wall having a fuel opening in its front side, an upright metal box within the interior of the hollow wall and provided with a fuel opening communicating with that in the hollow wall, said box having a partition between and spaced apart from its front and rear sides and extending from end to end across the entire back of the fuel openings, the upper edge of the partition terminating some distance below the top of the box to form a bridge wall, and a lining of heat resisting material across the front face of the partition and united to the ends of the fuel opening in the hollow wall, said lining extending from the base of the fuel opening to a plane above the upper side thereof.

5. A fire place comprising a hollow upright wall having a fuel opening in its front side, a sheet metal box within the hollow

wall extending from the base of the fuel opening to a plane some distance above the upper side thereof and having its front wall provided with a fuel opening registering 5 with that in the front side of the hollow wall, said box also having an upright partition between and spaced apart from its front and rear sides and extending from the base of the fuel opening to a plane some distance 10 above the upper side thereof and terminating at its upper end some distance below the top of the box forming an intervening space

between the partition and back of the box, said space having a smoke outlet, and a hollow partition within said space having a 15 cold air inlet and a warm air outlet, the latter opening into the interior of the hollow wall.

In witness whereof I have hereunto set my hand on this 8th day of March 1912.

GUSTAV STICKLEY.
